UNITED STATES PATENT OFFICE.

EDWARD G. GERMER, OF ERIE, PENNSYLVANIA, ASSIGNOR TO GERMER STOVE COMPANY, OF ERIE, PENNSYLVANIA, A CORPORATION OF PENNSYLVANIA.

DESIGN FOR A FIRE-FACE FOR GAS-STOVES.

49,265.

Specification for Design.

Patented June 27, 1916.

Application filed December 16, 1914. Serial No. 877,605. Term of patent 14 years.

To all whom it may concern:

Be it known that I, EDWARD G. GERMER, a citizen of the United States, residing in Erie, county of Erie, and State of Pennsylvania, have invented a new, original, and ornamental Design for Fire-Faces for Gas-Stoves, of which the following is a specification, reference being had to the accompanying drawings, forming part thereof.

The figure is a perspective view of a fire face of a gas stove showing my new design in which there is a depressed frame with strips extending vertically across the rear

face of the frame and projecting outwardly from sail rear face with a curved surface having a vertical axis, the rear face of the frame being on a plane relatively to the strips intersecting the curve formed by the strips continued.

I claim:

The ornamental design for a fire face for gas stoves as shown and described.

EDWARD G. GERMER.
